DISPLAY RACK FOR CONTAINERS OF SPICES OR THE LIKE

Lloyd M. Hartford, 833 Westover St.,
Battle Creek, Mich. 49015

Filed Sept. 7, 1966, Ser. No. 3,764

Term of patent 14 years

(Cl. D80—9)

FIGURE 1 is a perspective view of the display rack for containers of spices or the like showing my new design.

FIG. 5 is a cross sectional view taken on line V—V of FIG. 4.

FIG. 6 is a cross sectional view taken on line VI—VI of FIG. 2.

I claim:

The ornamental design for a display rack for containers of spices or the like, substantially as shown and described.
